FOLDING TRAY TABLE

Russel Wright, New York, N. Y., assignor to
 Shwayder Brothers, Ecorse, Mich., a corpora-
 tion of Colorado

Application March 3, 1951, Serial No. 14,374

Term of patent 14 years

(CL. D33—14)

To all whom it may concern:

Be it known that I, Russel Wright, a citizen of the United States, residing at New York city, in the county of New York and State of New York, have invented a new, original, and ornamental Design for a Folding Tray Table, of which the following is a specification, reference being had to the accompanying drawing, forming part thereof, in which:

Fig. 1 is a perspective view of a folding tray table showing my new design;

Fig. 2 is a top plan view thereof;

Fig. 3 is a fragmentary sectional view taken on line 3—3 of Fig. 2 and looking in the direction of the arrows;

Fig. 4 is a fragmentary sectional view taken on line 4—4 of Fig. 2 and looking in the direction of the arrows; and

Fig. 5 is a broken side elevational view thereof, with the leg support omitted.

I claim:

The ornamental design for a folding tray table, substantially as shown.

RUSSEL WRIGHT.
